UNITED STATES PATENT OFFICE.

WILLIAM N. RETTINGER, OF BOURBON, INDIANA.

WASHING-MACHINE.

No. 830,172.

Specification of Letters Patent.

Patented Sept. 4, 1906.

Application filed March 17, 1905. Serial No. 250,582.

To all whom it may concern:

Be it known that I, WILLIAM N. RETTINGER, a resident of Bourbon, in the county of Marshall and State of Indiana, have invented 5 certain new and useful Improvements in Washing-Machines; and I do hereby declare the following to be a full, clear, and exact description of the invention, such as will enable others skilled in the art to which it app 10 pertains to make and use the same.

My invention relates to an improvement in washing-machines, the object of the invention being to provide improvements of this character which can be easily operated 15 to most effectually wash material placed therein, which can be adjusted to permit easy removal of goods or material therefrom in convenient position to have the water wrung therefrom by a wringer carried by the 20 washer-supporting frame; and the invention consists in certain novel features of construction and combinations and arrangements of parts, as will be more fully herein-after described, and pointed out in the claims.

25 In the accompanying drawings, Figure 1 is a perspective view illustrating my improvements, and Fig. 2 is a view in section.

1 represents a supporting base or platform, provided at one end with a wringer-frame 2, 30 extending upward from the base and having strengthening-braces 3, and said frame is of the proper height from the base to support a wringer at its top for a purpose which will hereinafter appear. At the other end of base 1 an inclined standard 4 is located and supports a notched bar 4^a. Near the wringer end of the base 1, on a cross-bar 5, a bar 5^a is mounted and provided with an opening or bearing 6 in its upper edge, said 40 opening or bearing being in a lower plane than the notch in bar 4^a.

7 represents a cylindrical barrel or receptacle for the goods to be washed, the opening in one end through which the goods are inserted and removed being closed by a cover 8, secured in place by a cross-bar 9, having any suitable fastening and provided with a crank 10, as shown. The opposite end of the barrel 7 is provided with a journal 11, adapted to enter the opening or bearing 6, while the crank 10 rests in the notch in bar 4^a.

when the barrel is supported at an incline and can be readily revolved by crank 10 to effectually wash the goods contained therein. When the washing is completed, the barrel 55 can be swung to a vertical position beside frame 2 and the goods passed through the wringer as they are removed from the barrel, the drained water finding its way back into the barrel, from which it can be removed 60 through suitable openings in the barrel, normally closed by plugs or otherwise.

Various slight changes might be made in the general form and arrangement of the parts described without departing from my 65 invention, and hence I would have it understood that I do not restrict myself to the precise details set forth, but consider myself at liberty to make such slight changes and alterations as fairly fall within the spirit and 70 scope of my invention.

Having fully described my invention, what I claim as new, and desire to secure by Letters Patent, is—

1. In a washing-machine, the combination 75 of a base, a rotary barrel or tank, of upper and lower bearings on the base supporting said barrel or tank in an inclined position, said barrel or tank having a pivotal support in the lower bearing, whereby it can be 80 moved to an upright position, and means for rotating said barrel or receptacle.

2. In a washing-machine, the combination with a base, a wringer-frame at one end of the base, and an inclined notched bar at the 85 other end, of a barrel or tank pivotally connected at one end to the base near the frame, and having rotary mounting, and a crank on the other end of the barrel or tank to rest in the notched bar when the barrel is in an in- 90 clined position.

3. In a washing-machine, the combination with a base, a cross-bar thereon, and a bar connected to said cross-bar, of a barrel or tank having a combined rotary and pivotal 95 mounting in said last-mentioned bar, a wringer-frame at one end of the base, a crank secured to the barrel, and a notched bar to receive the crank and support the barrel in an inclined position.

4. In a washing-machine, the combination with a base, a barrel and a combined pivotal

and rotary mounting for the barrel on the base, a cover closing an opening in the barrel end, a cross-bar secured to the barrel and holding said cover in place, a crank on said cross-bar, and a notched bar to receive the crank and support the barrel in an inclined position.

In testimony whereof I have signed this specification in the presence of two subscribing witnesses.

WM. N. RETTINGER.
